BOTTLE

James E. Plummer, Toledo, Ohio, assignor to Owens-Illinois, Inc., Toledo, Ohio, a corporation of Ohio

Filed Aug. 24, 1965, Ser. No. 86,696

Term of patent 14 years

(Cl. D58—9)

FIG. 2

FIG. 1 is a front perspective view of a bottle showing my new design; and

FIG. 2 is a rear perspective view thereof.

The characteristic features of this design reside in the configuration shown in full lines on the drawing.

I claim:

The ornamental design for a bottle, substantially as shown and described.
